[57] CLAIM

The ornamental design for a t-braced knee support pillow, as shown and described.

DESCRIPTION

FIG. 1 is a perspective view of a t-braced knee support pillow showing my new design, the broken-line showing of a shorts-clad user is for illustrative purposes only and forms no part of the claimed design;

FIG. 2 is a bottom plan view of a t-braced knee support pillow;

FIG. 3 is a front elevational view, the rear elevational view being a mirror image thereof;

FIG. 4 is a left side elevational view, the right side elevational view being a mirror image thereof; and,

FIG. 5 is a top plan view.

FIG. 4

FIG. 5

FIG. 3

FIG. 2
